UNITED STATES PATENT OFFICE.

JAMES H. GRAHAM, OF SAN FRANCISCO, CALIFORNIA.

AUTOMOBILE-RADIATOR.

1,006,747.

Specification of Letters Patent.

Patented Oct. 24, 1911.

Application filed January 21, 1911. Serial No. 603,832.

To all whom it may concern:

Be it known that I, JAMES H. GRAHAM, citizen of United States, residing in the city and county of San Francisco and State of California, have invented new and useful Improvements in Automobile-Radiators, of which the following is a specification.

This invention relates to radiators, and more particularly to radiators used in conjunction with engines employing water for cooling their parts.

The object of the present invention is to increase the cooling efficiency of radiators; and to provide simple, effective radiators adaptable to a variety of working conditions.

It is a desideratum to provide a radiator whereby the cooling fluid from the engines can be quickly reduced in temperature and to prevent the discharge of air passing through the radiator toward the engine, thus avoiding the possibility of conveying grit, dust or other foreign material toward the working parts of the engine.

The invention consists of the parts and the construction and combination of parts, as hereinafter more fully described and claimed, having reference to the accompanying drawings, in which—

Figure 1 is a front view of the radiator. Fig. 2 is a central vertical transverse section of the same.

In accomplishing the objects of my invention I may employ a radiator A of any preferred style or form, having at its upper portion the water head 2 and at its lower portion the water chamber 3, to the upper of which heated water is conveyed through a pipe 4 from an engine, not necessary to be shown, and from the upper water head 2 the heated water passes downwardly through a series of water tubes or conductors 5 which may be of any design, and between which there are formed passages 6 through which air may flow in a general downward vertical course to the bottom water chamber 3.

In order to insure the general downward vertical flow of air through the radiator, I fix upon the front thereof, a removable plate 7 by suitable fastening devices 8 secured thereon, and which project transversely through the radiator and through a removable back plate 9 which will be secured against the rear surface of the radiator by the nuts 10 screwed on the bolts 8.

The front plate 7 extends from the bottom of the radiator upwardly and terminates sufficiently below the water head 2 to form an opening 11 whereby a sufficient volume of air may flow into the radiator between the several water tubes or conductors 5. Air which flows in through the opening 11 is deflected downwardly by means of a removable deflector or sectional plate 12 which is in area approximately equal to the area of the air opening 11, and which is removably secured to the rear of the radiator by suitable locking devices, as bolts 13.

When this radiator is used in combination with a motor vehicle and the latter is driven, a natural draft is caused to flow into the opening 11 above the front plate 7 by the pressure of the air against the radiator. This draft of air will flow downwardly between the conductors 5, and front and back plates 7 and 9, and may flow through vertical passageways 14 formed through the lower water chamber 3 and into a common discharge casing 15, or it may flow forwardly or rearwardly into a suitable housing 16 which may be attached to the radiator.

In certain cases it is desirable to accelerate the flow of air vertically through the inclosed radiator, as by means of a suitable mechanical device, here represented as a blower 17, mounted upon a shaft 18 supported upon or adjacent the radiator. While in operation, the blower exhausts the air from the housing 15 and discharges it, as at 19. This blower may be of any desired character and may be driven by any suitable source of power and may be mounted directly upon an engine or other shaft, it being understood that the purpose of supplying the blower 17 is to cause an induced draft of greater velocity through the closed radiator, and any form of blower mounted in a convenient position will be effective to accomplish this result.

A plurality of the passageways 14 may be provided in the lower water chamber 3, as shown in Fig. 1, and air flowing vertically downward through the radiator may pass through these passageways 14; or, if desired, these passageways may be closed and all of the air caused to flow forwardly or rearwardly through the housing 16 which communicates with the housing 15 from which the air passes to the blower 17 whereby it is discharged at 19. Further provi-

sion may be made for the incoming of a large volume of air at greater speed by a swinging plate 20, which is pivoted at 21 upon the back radiator plate 9, and when 5 the pressure of air in the radiator between the plates 7 and 9 is sufficiently great the swinging plate 20 may freely open to allow a portion of the air to flow outwardly and downwardly through a rear housing 22 at- 10 tached to the radiator.

By my form of construction the air, which passes inwardly through the opening 11 above the front plate 7 of the radiator, is led downwardly and vertically between the 15 fluid conduits 5 beginning at their uppermost portion where they have the greatest temperature and flowing downwardly effectively cooling the water in the conductors, the air being finally discharged from 20 the housing 15.

In certain climates it may be desirable to prevent the admission of very cold air at the front of the radiator above the plate 7, in which event the removable section or 25 plate 12 may be uncoupled from the rear of the radiator and shifted to the front thereof so as to close the opening 11. This will then produce an opening at the rear of the radiator at the position occupied by the 30 plate 12 in Fig. 2. Thus the air which would be drawn into the radiator would be of somewhat higher temperature than that at the front of the radiator which is generally subjected directly to the atmosphere and pressure of the air when the radiator is mounted upon a motor vehicle.

It will be understood that, if desired, the air may be taken into the radiator through its vertical legs 23 by forming appropriate 40 openings at their upper portion adjacent the water head 2 when the desired cooling effect would be produced by leading the incoming air vertically downwardly through the radiator.

45 In operation when the radiator is being moved forward, as when mounted upon a motor vehicle or when the blower 17 is being operated, a draft of air is created past the water conduits 5 and downwardly be- 50 tween the front and back plates 7 and 9 respectively, which are secured to the ra- diator. Thus all of the air which is taken in at the opening 11 adjacent the water head 2 is confined during its downward flow be- 55 tween the plates 7 and 9 and compelled to circulate between the water conductors 5, whereby the maximum cooling efficiency of the air so drawn in through the opening 11 is rendered effective in the radiator the air 60 finally discharged from the housing 15.

The particular feature of this invention is in the distribution of the air through the radiator between the front and back plates 7 and 9 which are secured to the radiator, 65 against the conductors 5.

If desired, suitable deflectors as 24 may be inserted to distribute the flow of air through the radiator.

Having thus described my invention, what I claim and desire to secure by Letters Patent is—

70 1. A radiator comprising a water receiving head and a foot chamber, spaced conductors connecting said water head and chamber, a covering for one side of the radiator conductors to prevent air from passing transversely through the radiator, a plate covering the opposite side of the radiator and terminating short of the water head so as to leave an opening for the admission of air between the spaced conductors, and means at the bottom of the radiator to effect the discharge of air from between the front and back plates.

75 2. A radiator comprising a substantially closed structure having a water receiving head at its upper portion and a water chamber at its lower portion, spaced water conductors connecting said parts, a front plate and a back plate embracing said water conductors, one of said plates being shorter than the other to form an opening whereby air may be admitted at the upper portion of the radiator and caused to flow downwardly between the spaced conductors embraced by the front and back plates and eventually discharged at the lower portion of the radiator.

80 3. A radiator having an upper water receiving head and a lower discharging foot, suitable water conductors of a width substantially equal to the width of the water head connecting said member to the water foot, front and back plates embracing said water conductors, one of said plates terminating sufficiently below the water head and forming an opening for the admission of air between said plates embracing the conductors, and means for inducing the current of air to flow vertically downwardly through the radiator between the spaced conductors.

85 4. A radiator having an upper water receiving head and a lower discharging foot, suitable water conductors of a width substantially equal to the width of the water head connecting said member to the water foot, front and back plates embracing said water conductors, one of said plates terminating sufficiently below the water head and forming an opening for the admission of air between said plates embracing the conductors, and means for inducing the current of air to flow vertically downward through the radiator between the spaced conductors, said means including a rotary fan.

90 5. A radiator having an upper water receiving head and a lower discharging foot, suitable water conductors of a width substantially equal to the width of the water head connecting said member to the water

foot, front and back plates embracing said water conductors, one of said plates terminating sufficiently below the water head and forming an opening for the admission of air 5 between said plates embracing the conductors, means for inducing the current of air to flow vertically downwardly through the radiator between the spaced conductors, said means including a rotary fan, and housings 10 into and through which the air may be discharged.

6. A radiator having an upper water receiving head and a lower discharging foot, suitable water conductors of a width substantially equal to the width of the water head connecting said member to the water foot, front and back plates embracing said water conductors, one of said plates terminating sufficiently below the water head and

forming an opening for the admission of air between said plates embracing the conductors, means for inducing the current of air to flow vertically downwardly through the radiator between the spaced conductors, said means including a rotary fan, housings 25 into and through which the air may be discharged, and an automatic controlling gate, disposed adjacent to the lower end of the radiator and normally closing and opening therein.

In testimony whereof I have hereunto set my hand in the presence of two subscribing witnesses.

JAMES H. GRAHAM.
